UNITED STATES PATENT OFFICE.

SAMUEL CHILD, JR., OF BALTIMORE, MARYLAND.

IMPROVEMENT IN VAPOR-STOVES.

Specification forming part of Letters Patent No. 57,288, dated August 21, 1866.

To all whom it may concern:

Be it known that I, SAMUEL CHILD, Jr., of Baltimore, in the county of Baltimore and State of Maryland, have invented certain new and useful Improvements in Vapor-Stoves; and I hereby declare the following to be a full, clear, and exact description of the same, reference being had to the accompanying drawing, in which is represented a longitudinal section of that part of the stove to which my improvements are applied.

My invention relates to that class of stoves in which petroleum, naphtha, or other similar volatile fluid, when vaporized, is employed as a heating agent. In these stoves, as is well-known, the fluid is, by means of hydrostatic pressure, forced through pipes leading from a fluid-reservoir into a retort or heating-chamber, where it becomes vaporized, and in this state issues from a burner or jet formed in the top of the retort.

In Letters Patent heretofore granted to me I have described a method whereby the supply of fluid to the retort is regulated by locating the valve or other suitable device used for this purpose at or near the point where the fluid enters the retort. The advantages possessed by an apparatus thus constructed over the apparatus ordinarily employed in vapor-stoves are fully set forth in the Letters Patent above referred to, and need not be repeated here.

My present invention more particularly relates to improved arrangements of parts for carrying the above-mentioned method into effect; and it consists substantially in the combination, with the retort-pipe and vaporizing-chamber of a vapor-stove, of a tubular valve under such an arrangement that the hollow valve-rod by which the supply of fluid to the vaporizing-chamber is regulated shall also form the medium through which the liquid is conducted into the said chamber.

To enable others skilled in the art to understand and use my invention, I will now, by reference to the accompanying drawing, proceed to describe the manner in which the same is or may be carried into effect.

The parts of the stove to which my improvements are applied consist of the retort-pipe A and retort or vaporizing-chamber B. The retort has screwed in its top a cap, C, in which

an orifice or burner, c, is formed to permit the escape of the gas generated in the retort. To the top of the cap are secured conductors D, which support a heater-cap, E.

The end of the retort B is secured on the retort-pipe A by means of a screw, which engages with a corresponding screw on the end of the retort-pipe. An elbow-joint, F, is attached to the rear end of the retort-pipe, in the top of which the upright pipe which leads from the fluid-reservoir is screwed at G. The end of the joint F is extended back on the prolongation of the retort-pipe A, and is cored at f, so as to form a bearing for the valve-rod, about to be described.

The device for regulating the flow of the petroleum or other fluid from the reservoir into the retort B consists of a tubular valve rod or stem, a. This rod may be made hollow throughout its whole length, as shown in the drawing, or, if preferred, that part of it in rear of the point where the fluid enters the retort-pipe from the reservoir-pipe can be left solid.

Small holes b b are formed in the tubular stem a, through which the fluid in the retort-pipe, by the pressure induced by the column of fluid in the upright reservoir-pipe, is made to enter the interior of the stem. These holes may be formed in the tubular rod at any point within the retort-pipe, and they may vary in number, although I have found that the two holes shown in the drawing are sufficient for all practical purposes.

In that end of the retort-pipe A which is secured to the retort B is tightly fastened a plug or stopper, d. This plug is cored so that its interior diameter will correspond with the diameter of the valve-rod, and a screw-thread, x, is cut or turned upon its interior surface, which fits a similar thread, y, formed on the front end of the valve-rod a. The valve-rod, which is thus supported in bearings f and d at its rear and front ends, extends a suitable distance beyond the plug d into the retort B, so that the fluid which enters through the holes b b is free to flow through the tubular rod and drop from its open end into the retort.

The supply of oil to the retort can be stopped at pleasure by revolving the rod a in its bearings by means of the handle m, attached to that end of the rod which extends out through the elbow-joint F. When this handle is turned

to the right the valve-rod is carried forward by means of the screw *x*, which engages with the screw *y* until its front end is pressed firmly against the front of the chamber *B* at *s*, closing the opening in its end and preventing the further flow of the oil into the retort.

A stud or projection, *n*, of suitable size to fit the open end of the rod, may be placed in the front part of the retort in such position that it will enter the tubular end of the valve-rod, forming a plug for the purpose of more effectually preventing the fluid from entering the retort. This plug, however, is not essential to the effective working of the apparatus.

It will therefore be seen that the front end of the tubular rod *a*, from which the fluid enters the retort, is also used as a valve for regulating or cutting off the supply of fluid, the front of the vaporizing-chamber forming the valve-seat.

When the apparatus is used the fluid enters the retort-pipe at *G*, and, being prevented by the plug or stopper *d* from entering the retort directly from the retort-pipe, makes its way through the holes *b b* into the tubular valve-rod *a*. If the end of the rod within the retorts be open, as represented in the drawing, the fluid flows through the rod and enters the retort, where it is vaporized and discharged through the orifice or burner *c*. When it is desired to stop the further generation of the gas the handle *m* is turned so as to press the front end of the valve-rod firmly and tightly against the valve-seat *s*. By this means the

fluid is kept within the tubular rod, and the supply of fluid being thus cut off, the flame from the burner *c* is almost instantaneously extinguished.

The valve-seat *s* may project out into the vaporizing-chamber any desired distance; but I have found it best to construct it as shown in the drawing.

A cap, *p*, within which is a metal washer, *r*, with packing of suitable material for making a tight joint, is screwed over the end of the elbow-joint *F*, from which the rod projects.

Having described my invention and the manner in which the same is or may be carried into effect, what I claim, and desire to secure by Letters Patent, is—

The combination, with the retort-pipe and heating-chamber of a vapor-stove, of the tubular valve-rod operated upon the axis of the said retort-pipe, as described, under such an arrangement that the said rod, while regulating the supply of fluid to the heating-chamber, shall also constitute the medium through which the fluid is conducted into the said chamber, substantially as herein shown and set forth.

In testimony whereof I have signed my name to this specification before two subscribing witnesses.

SAML. CHILD, JR.
